(57) **CLAIM**

The ornamental design for a headgear component for a nasal mask assembly, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front and side perspective view of a headgear component for a nasal mask showing our new design, shown in a flat configuration;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a bottom plan view thereof;

FIG. 7 is a top plan view thereof; and,

FIG. 8 is an enlarged view of FIG. 2.

Where utilized, dashed broken lines are used to illustrate features of the headgear component for a nasal mask assembly that form no part of the claimed design. Dash-dot broken lines represent a boundary of the claimed design and form no part thereof.
